UNITED STATES PATENT OFFICE.

JOHN A. BEIRNS, OF DETROIT, MICHIGAN.

STARTER FOR INTERNAL-COMBUSTION ENGINES.

1,257,784.

Specification of Letters Patent. Patented Feb. 26, 1918.

Application filed December 9, 1912. Serial No. 735,623.

To all whom it may concern:

Be it known that I, JOHN A. BEIRNS, a citizen of the United States, residing at Detroit, county of Wayne, State of Michigan, have invented a certain new and useful Improvement in Starters for Internal-Combustion Engines, and declare the following to be a full, clear, and exact description of the same, such as will enable others skilled in the art to which it pertains to make and use the same, reference being had to the accompanying drawings, which form a part of this specification.

My invention relates to starters for internal combustion engines and the special object of my improvements is to provide an improved apparatus for controlling the electric starting mechanism on automobiles.

I secure this object in the device illustrated in the accompanying drawings, in which;

Figure 1, is an elevation partly in section of an apparatus embodying my invention, and so much of an automobile as is necessary to illustrate its connection therewith. The electric circuits are indicated diagrammatically.

Fig. 2, is an elevation of the same looking from the left of Fig. 1, parts toward the observer being removed and a part of the mechanism being shown broken away.

Fig. 3, is a detail illustrating the stop mechanism.

a is a fly wheel provided with gear teeth *b* around its periphery. *c* (Fig. 1) represents the floor of the body of the automobile in section. The floor *c* is slotted at *q* for the purpose hereinafter described. *d* represents a cross piece of the frame. *e* is the shaft of the starting motor. *f* is a spur gear wheel upon the shaft *e*. *g* is a counter shaft having a gear wheel *h* keyed thereon adapted to be driven by the spur wheel *f*. The shafts *g* and *e* bear in a housing *j* inclosing the gear wheels *f* and *h*. The shaft *g* is squared at its outer end at *i*. *k* is a gear wheel fitted upon the squared portion *i* of the shaft *g* and adapted to slide thereon. The hub of the gear wheel *k* is provided with a peripheral groove *m* adapted to receive a fork to shift the gear wheel *k* in the usual way. The shaft *g* is so located that when the gear wheel *k* is moved to its inner position it engages the gear teeth *b* on the fly wheel *a* and when moved to its outer position, as shown in Fig. 1, the shaft *g* is

free from the fly wheel *a*. *n* is a standard rising from the housing *j* and provided with a vertical slot 22. *o* (Fig. 1) is a standard rising from the cross piece *d*. *p* is a rod fitting and adapted to slide in the standards *n* and *o*. *r* is a cross head secured to the rod *p* and extending vertically upward into the slot *q* in the floor *c* of the body of the automobile. The cross head *r* is provided at 65 its upper end with a pedal or foot piece *s*. The operator may press the rod *p* forward by the action of his foot on the pedal *s* pressing the cross head *r* along the slot *q*.

u is an arm secured upon the rod *p*, its 70 outer end being forked and engaging in the slot *m* in the hub of the gear wheel *k*. *t* is a pressure spring interposed between the standard *n* and the arm *u* and acting to press the rod *p* to its rearward position so 75 as to carry the gear wheel *k* out of engagement, as shown in Fig. 1. *v* is a slot in the rod *p* toward its forward end where it slides through the standard *n*. *w* is a pawl pivoted at *x* (Fig. 2) to a stationary support and extending into the slot 22 in the standard *n* and adapted to engage in the slot *v* in the rod *p* when said slots register with each other. *y* is an armature on the pawl *w* and *z* is a magnet adapted to attract 80 the armature *y* to oscillate the pawl *w* and cause it to engage in the slot *v* on the rod *p*.

2 indicates a generator operated by the engine, in this case, the charging generator. The coil of the magnet *z* is interposed in a 90 circuit in which is the generator 2 so that when said generator is in operation, said magnet will be energized and act to engage the pawl *w* in the slot *v*. The slot *v* is so located that it shall register with the slot 95 22 in the standard *n* when the rod *p* is at its rearmost position and lock the rod in this position.

4 is a pin, or lug, extending laterally from the rod *p*. 100

5 is a switch box secured to an arm 6 which is supported by the cross piece *d*. 7, is a shaft bearing in the switch box 5. 8 is an arm keyed upon the shaft 7 and having a fork 9 at its outer end and, which fork 105 engages over the lug 4 so that a movement of the rod *p* shall actuate the arm 8 to turn the shaft 7. 10 is an arm on the shaft 7 in the switch box 5, its outer end being provided with a cavity. 11 is a block or contact plate adapted to reciprocate radially in the cavity at the outer end of the arm 10, 110

12 is a spring acting to force the block 11 outward. 23 is an arc of insulating material having its center at the center of the shaft 7 and closing the end of the switch box 5. The contact plate 11 moves along the inner surface of the arc 23. 14, 15 and 16 are contact pieces, their inner ends forming contact plates in the inner surface of the arc 23 and the outer ends formed to constitute binding posts. The contact pieces 14, 15 and 16 are spaced as shown in Fig. 1 so that the contact plate 11 may contact two of them at the same time for a short interval of its travel. 10

15 17 indicates the starting motor diagrammatically. 18 is a battery by which the motor 17 may be actuated. 19-19 represents conducting wires forming a part of the circuit between the contact pieces 14 and 20 16. 20 is a resistance coil interposed in the circuit with the conductors 19-19. 21-21 are conductors completing the circuit between the contact pieces 15 and 16 through the storage battery 18 and starting motor 17. 25 The operation of the above described device is as follows:

The engine being at rest the magnet z is not energized and the pawl w is disengaged from the slot v by a spring. The parts being in the 30 position shown in Fig. 1 the rod p is yieldingly held in its rearmost position by the spring t . The operator may press the cross head forward in the slot q by his foot acting against the pedal s , pressing the rod p forward against the resistance of the spring t and moving the gear wheel k toward its 35 engaging position with the gear teeth b . As the rod p moves forward, the arm 8 is actuated by the lug 4 turning the shaft 7, 40 which carries with it the arm 10, the contact plate 11 moving into contact with the contact piece 15 so that there shall be a circuit from the battery 18 to the contact piece 15, through the plate 11 to the contact piece 14, through the conductors 19 and 45 resistance 20 to the contact piece 16, thence through a conductor 21 and the motor 17 back to the battery 18, thus starting the motor 17 with a weak actuating current. After 50 the motor has been thus started the circuit is broken by the plate 11 moving out of contact with the contact piece 14. When the rod p is pressed further forward the teeth of the wheel k engage with the teeth b and 55 when well engaged the plate 11 passes over the contact piece 16 forming a connection between the plates 15 and 16 and completing the circuit through the conductors 21, battery 18 and motor 17 to give the full 60 starting current. When the engine is in operation the operator removes his foot from the pedal s and the rod p is returned to its off position by the action of the spring t

in which position the grooves v and 22 register with each other. The lighting generator now being actuated, the magnet z acts to cause the pawl w to engage in the groove v thus holding the parts locked as long as the engine is in operation. 6

It will be seen that in the above device 70 the motor is started gradually so that danger of overheating and clashing gears is avoided and the gears are engaged while the motor is moving slowly before the full power is applied to it so that there is no danger of 75 stripping the gears, and it is impossible to move the motor engaging part when the engine is in motion.

The motor is started before the gear wheels engage thus insuring that the wheels 80 shall come into proper relative position for their teeth to engage. The current is then shut off so that there is but little friction between the teeth until they are almost fully engaged when the full current is thrown on. 85

The wheels form a toothed engaging means.

What I claim is:

1. In an electric starter having a motor engine and generator, the combination of 90 mechanism for engaging and disengaging the motor and engine, a switch for controlling the circuit through said motor, means connecting said mechanism with said switch so that said circuit shall be open when said mechanism is in its initial position and shall be closed when said mechanism is engaged, and a mechanical lock operated by the current from the generator for actuating said lock to secure said mechanism in its initial 95 position, and an automatic means for returning said mechanism to its disengaged 100 position.

2. The combination of a starting motor, 105 an engine, means for engaging and disengaging said motor with the engine, a switch having three contact pieces properly spaced, a contact plate adapted to move into position to successively engage said contact pieces in pairs, a circuit containing a resistance between the first and last of said contact pieces, a circuit including the battery and motor between the second of said contact pieces and the last thereof, said contact plate being connected so as to be moved by 110 said engaging mechanism, said second circuit being closed after full engagement of said teeth and at an interval after the breaking of the first circuit.

In testimony whereof, I sign this specification in the presence of two witnesses. 120

JOHN A. BEIRNS.
